UNITED STATES PATENT OFFICE.

REUBEN E. BECHTOLD, OF FORT WAYNE, INDIANA, ASSIGNOR TO S. F. BOWSER & COMPANY, INC., OF FORT WAYNE, INDIANA, A CORPORATION OF INDIANA.

MOTOR FOR DISPENSING PUMPS.

Application filed May 13, 1921. Serial No. 469,155.

This invention relates to fluid pressure motors, and especially to a motor driven by compressed air for operating pumps for dispensing liquids, such as gasoline and similar commodities.

The invention has for its object the provision of mechanism of the class named which shall be of improved construction and operation. It is exemplified in the combination and arrangement of parts shown in the accompanying drawings and described in the following specification, and it is more particularly pointed out in the appended claims.

In the drawings—

Fig. 1 is an elevation, with parts broken away, of a motor embodying one form of the present invention;

Fig. 2 is a vertical section of the motor shown in Fig. 1;

Fig. 3 is an elevation looking from the right in Fig. 1 with parts in section;

Fig. 4 is a horizontal section on line 4—4 of Fig. 2;

Fig. 5 is a horizontal section on line 5—5 of Fig. 2;

Fig. 6 is a fragmentary horizontal section showing the valve construction;

Fig. 7 is a vertical section on line 7—7 of Fig. 6;

Fig. 8 is a bottom plan of the valve; and

Fig. 9 is a fragmentary section on line 9—9 of Fig. 5.

Piston type pumps for dispensing gasoline usually comprise a plunger working in a cylinder which is connected with gearing provided with a crank handle to be operated by hand. These pumps are practically all made single acting, that is, they are made to discharge liquid on the upward stroke only and require the plunger to be returned to its lowermost position to complete each cycle.

The present invention contemplates a compressed air driven motor especially adapted to take the place of a hand crank for operating pumps of the character mentioned above. In Figs. 1 and 2 there is shown a motor having a base casting 10 provided with a bracket 11 by means of which the motor may be secured to the casing of a pump to be operated. The motor is provided with a cylinder 12 in which a piston 13 is arranged to reciprocate, the piston having a rectangular rod 14 secured thereto and provided with rack teeth 15 formed directly

thereon. The cylinder 12 is provided with an air-tight connection with a top casting 16 having flanges 17 for receiving the upper end of the cylinder. A similar connection is provided between the lower casting 10 and the lower end of the cylinder, and the two castings are secured together by stay rods 18. The motor rack 14 extends through an opening 19 in the upper casting 16 and a pair of packing plates 20 and 21 are provided with openings which closely fit the rack bar 14. The packing plates 20 and 21 have their faces ground to fit one another closely, and the plate 21 has its upper face accurately fitted to a flange 22 extending downwardly from the casting 16. A retaining plate 23 is secured to the casting 16 and is provided with recesses containing springs 24 which bear against the lower face of the plate 20 and force the plates 20 and 21 into contact with one another, and the upper plate 21 against the flange 22. The plates 20 and 21 are free to move laterally, except for their engagement with the rack bar 14.

The teeth 15 mesh with the teeth of a pinion 26 splined on a shaft 27 journaled in the casting 16. A second gear 28 is secured to the shaft 27 and meshes with a pinion 29 fastened on a shaft 30. One end of the shaft 30 is provided with a coupling member 31 by means of which it may be coupled with the shaft of a liquid dispensing pump. The opposite end of the shaft 30 is provided with a keyway 32 by means of which a hand crank may be attached to the shaft to operate the motor and pump in case of failure of the air pressure. Normally the end of the shaft bearing the keyway 32 is enclosed in a removable cap 33 threaded into a cover plate 34 secured to the casting 16 by screws 35. The casting 16 is provided with oil chambers 36 and oil rings 37 to supply lubricant to the shafts 27 and 30 from these chambers. U-washers 38 enter grooves in the shafts 27 and 30 and hold these shafts against longitudinal movement. A cap 39 closes the bearing opening at one end of the shaft 27. A roller 40 is journaled on the shaft 30 opposite the rack 14 to hold the rack properly in mesh with the pinion 26.

Air is admitted to the lower end of the cylinder 12 through a pipe 41 which communicates with a cored opening 42 in the lower casting 10. The upper end of the cylinder 12 communicates with a cored port

43 in the casting 16, the port 43 being arranged to register with an opening 44 in a valve seat 45. A similar opening 46 registers with the upper end of the pipe 41. A 5 valve casing 47 rests upon an outwardly extending flange 48 on the valve seat 45, and the casing and seat are held in place by bolts 49. A valve 50 rests upon the upper face of the valve seat 45 and is 10 provided with a valve stem 51 extending through a packing gland 52 in the casing 47. The valve 50 is held against rotation relative to the stem 51, but is free to slide in the direction of the axis of the stem and is 15 resiliently held upon its seat by a compression spring 53. The valve 50 is oscillated about the axis of its stem 51 by a handle 54 secured to the upper end of the stem. As shown in Figs. 2 and 5, the handle 54 is 20 provided with laterally extending lugs 55 which bear against stops 56 on a horizontally sliding head 57. The plunger 67 is seated in a recess in a projection 72 of the lever 66 and has its opposite end slidably mounted in a 25 bracket on the casing 97, as shown in Figs. 2 and 5. The head 57 is connected with a rod 58 slidably mounted in the controller casing 97 and surrounded by a coil spring 59 which normally presses the head 57 30 to the right, as viewed in these figures, and thus retains the handle 54 in central position.

A brake 60 is arranged to bear upon the periphery of the pinion 29, as shown in 35 Fig. 2, the brake being supported by a pair of links 61 which are carried on a member 62 pivoted on a cross-rod 63 supported by the casting 16. The member 62 is provided with an adjusting screw 64 the lower end of which 40 bears upon a ledge 65 projecting from a lever arm 66. The lever arm 66 engages the end of a plunger 67 resiliently pressed to the right by a spring 68, as shown in Fig. 2. 45 A pair of links 69 are pivotally connected to opposite sides of the brake member 60, the opposite ends of the links being pivoted upon a cross-rod 70 supported by the casting 16. It will be seen that the expansion 50 of the spring 68 will tend to exert a lifting force on the link 61 and that this force will cooperate with the links 69 to press the brake 60 into engagement with the pinion 29 and thus resist downward movement of the rack 14. A release bar 71 is slidably 55 mounted in the casing 97 of the control mechanism in position to engage one of the shoulders 55 on the hand lever 54 when the lever is swung in a clockwise direction, as viewed in Fig. 5. This release bar 71 bears 60 against a projecting arm 72 on the lever 66 in position to compress the spring 68 and lower the brake 60 so as to permit downward movement of the rack 14 under the control of the valve mechanism in a manner 65 to be explained.

The operation of the valve mechanism will best be understood from Figs. 2, 6, 7 and 8. The valve seat 45, as shown in Fig. 7, is provided with a port 73 communicating with a pipe 75 through a cored opening 76 in the 70 casting 16. The pipe 75 is provided with a coupling 77 for connection with any suitable source of compressed air or other actuating fluid. The opening 73 in the valve seat 45 75 communicates with the interior of the casing 75 47 so that the interior of the casing is constantly supplied with fluid under pressure. This will assist the spring 53 in holding the valve 50 upon its seat. A port 78 in the valve seat 45 registers with a cored opening 80 79 in the casting 16, which in turn is connected with a discharge pipe 80 having a muffler 81 connected therewith for deadening the noise caused by the discharge of the air from the motor. The port 78 opens upwardly through the valve seat 45 is communication with an arc-shaped groove 82 on the lower face of the valve 50. The valve 50 is cut away at one side and notched to provide inlet ports 83 and 84, respectively. 85 When the handle 54 is moved to shift the valve 50 in a counter-clockwise direction, as viewed in Fig. 6, the port 83 will be brought into registration with the port 46 in the valve seat 45. At the same time the groove 82 will be moved away from the port 46 but 90 will remain in registration with the port 44. This will connect the lower end of the cylinder 12 with the source of compressed air, while the upper end of the cylinder is open 100 to the atmosphere and the piston 13 will be caused to rise in the cylinder to operate the pump. The upward movement of the piston will rotate the pinion 29 in a clockwise direction, as viewed in Fig. 2, so that the rotation of the pinion will automatically release the brake 60 due to the relative angle of the link 69. If at any time during the upward movement of the piston the handle 54 is 105 released, it will automatically be brought to a central position by the spring 59 and the groove 82 in the valve 50 will then connect both the upper and lower ends of the cylinder with the discharge port 78. The piston will then come to rest and be held 110 against downward movement by the brake 60. If the handle 54 is again operated to raise the piston the motion will continue from the point where it was arrested until the upper end of the stroke is reached, or 115 until it is again checked by release of the handle. Instead of continuing the upward movement the piston may be returned to its lowermost position by moving the lever 54 in the opposite direction. This movement 120 will rotate the valve 50 in a clockwise direction, as viewed in Fig. 6, and will bring the port 84 into registration with the port 44 which 125 communicates with the upper end of the cylinder. At the same time the port 46 130

will remain in communication with the discharge outlet and the piston will be positively moved downward under the pressure of the air in the upper end of the cylinder.

- 5 The same movement of the handle 54 which operates the valve 50 for a downward movement of the piston will also bring the lower portion of the shoulder 55 into contact with the outer end of the brake release rod 71 and move the lever 66 in a direction to release the brake 60.

In a device of this character it is desirable that the piston shall be returned to its extreme downward position after each opera-

- 15 tion so that on a subsequent operation a full stroke will be made to deliver full measure of liquid. For this reason interlocking mechanism is provided to prevent shifting the lever 54 to a raising position after it has 20 once been moved to lower the piston until the piston has reached its extreme downward position. This mechanism is shown in Figs. 2, 5 and 9 and comprises a bar 85 mounted to slide in notches 85' formed in brackets

- 25 86 and 87 in the control casing 97. The bar 85 is provided with a head 88 having a transverse groove 89 therein in which an upwardly projecting stud or roller 90 carried on the lever 54 is arranged to travel. The bar 85 is provided with an opening in which a pin 91 is slidably mounted in position to bear against the face of the rack 14. A spring normally presses the pin 91 into contact with the rack. As shown in Fig. 9, 30 the face of the rack 14 is provided with a notch 93 in position to be engaged by the end of the pin 91 when the rack is in its lowermost position. When the lever 54 is moved to admit fluid to the cylinder for raising the rack, the beveled edge of the notch 93 will permit the rack to raise and force the pin out of the notch. When the lever 54 is moved in a clockwise direction, as viewed in Fig. 5, to cause a lowering of the

- 35 rack, the pin 91 will be drawn to the right in Fig. 5 until it passes the edge of the rack 14 and will then be pressed by the spring 92 past the corner of the rack so that the bar 85 will be locked against return movement.

- 40 50 This prevents the lever 54 being moved in a direction to raise the rack; however, it does not hold the valve 50 in position to supply fluid to the cylinder to lower the rack. In order to lower the rack it will be

- 55 necessary to hold the lever 54 and when the rack comes to its lowermost position the notch 93 again comes opposite the pin 91. The lever 54 may then be returned to neutral position and be operated for again raising the rack. The brake 60 may be so regulated by the adjusting screw 64 that the brake will not be released by the movement of the lever 54 for lowering the rack until after the pin 91 has passed the edge of rack 14 and locked the lever against return movement. An ad-

justing screw 94 is provided for limiting the movement of the lever 54 to control the amount of opening of the port 44 for lowering the rack, thus controlling the speed of lowering. Any lower speeds can be obtained by opening or closing valve 50 more or less by means of the control lever 54. A cap 95 is secured to the upper end of the rack 14 and provides a weather shield for the rack and for its passage into the cover for the 70 motor. A casing 96 is carried by the upper and lower castings 10 and 16 and encloses the cylinder and other parts between the two castings. 75

I claim:—

1. A motor comprising a cylinder and a piston arranged to reciprocate therein, a hand operated valve for selectively admitting fluid under pressure to opposite ends of said cylinder, and a lock for positively preventing 80 movement of said valve in a direction to produce reversal of said piston during movement thereof in one direction.

2. A motor comprising a cylinder having a reciprocating piston therein, hand controlled means for selectively admitting fluid under pressure to opposite ends of said cylinder to move said piston in opposite directions, and means for automatically locking 90 said hand controlled means to prevent reversal thereof during movement of said piston in one direction.

3. A motor for a liquid dispensing pump comprising a cylinder having a reciprocating piston therein, a reciprocating rack operated by said piston, hand actuated means for controlling the movement of said piston and rack, and locking means for said hand actuated means to retain said hand actuated means in the position to which it has been 100 moved when said means is actuated to cause reciprocation of said piston and rack in one direction.

4. A motor comprising a cylinder having a reciprocating piston therein, a rack connected with said piston, a valve for controlling the admission of fluid under pressure to opposite ends of said cylinder to reciprocate said rack, a hand lever for controlling said valve, a lock for holding said hand lever to 110 prevent reversal of said piston when said piston is moving in one direction but permitting reversal of said piston when said piston is moving in the opposite direction, and means for automatically moving said hand lever to a neutral position and connecting opposite ends of said cylinder to atmosphere when said hand lever is released. 115

5. A motor comprising a cylinder having a reciprocating piston therein, valve mechanism for controlling said piston and a lever for shifting said valve mechanism, resilient means for holding said hand lever in neutral position in which both ends of said cylinder 120 are in communication with the atmosphere, 125

a brake for preventing accidental return movement of said piston but inoperable to prevent forward movement thereof, resilient means normally holding said brake in operative position, and mechanism for automatically releasing said brake when said hand lever is actuated to produce the return movement of said piston.

6. A motor comprising a reciprocating rack, hand actuated mechanism for controlling the movement of said rack, and means for preventing reversal of said control mechanism during the movement of the rack

in one direction, said means comprising an automatically actuated lock for holding said control mechanism in fixed position when it has been actuated to produce movement of said rack in said direction and to retain said hand actuated mechanism in said position until the limit of movement of the rack in said direction has been reached.

In testimony whereof I have signed my name to this specification on this 7th day of May, 1921.

REUBEN E. BECHTOLD.
